UNITED STATES PATENT OFFICE.

LAWRENCE EDWIN ARNESON, OF MORRIS, ILLINOIS, ASSIGNOR TO MORRIS PAPER MILLS, OF CHICAGO, ILLINOIS, A CORPORATION OF ILLINOIS.

FOLDED PAPER BOX.

Application filed November 22, 1926. Serial No. 149,841.

This invention relates to folded paper boxes, and more particularly to the type of box made from a paper blank which is cut and folded in a manner to permit the box to be readily set up and locked in set up position.

One of the objects of my invention is to provide a box which is cheap, simple in construction, yet durable and efficient in service.

Another object of my invention is to provide a box which may be made from a single blank, the blank being folded along hinged lines to form the side and end walls and being provided with parts which cooperate to hold the box in locked position when it is once set up, the cooperating parts assuming their engaging positions of their own accord when the box is folded into the proper set up position.

Another object of my invention is to provide a box made from a paper blank having a main panel and side and end panels hinged to the edges thereof, the end panels being provided with end flaps which are adapted to be folded to overlie the end panels and to enclose flaps on the ends of the side panels, and being further provided with a locking flap on its inner edge adapted to assume a position parallel to the main panel and to engage the inner side thereof when the box is folded in set up position, the locking flap having wedged extensions at its edges which on being pushed into position wedge against the side panels and finally become automatically seated and locked in slits provided at the hinge between the side panels and the main panel in a manner to lock the box in set up position.

A further object of my invention is to provide a box of the type described in the above stated objects in which the locking flap is disposed at right angles to the end panel in a manner to form a reinforce for the end panel and the overlapping flap provided on said end panel.

These and other objects are accomplished by means of the arrangement disclosed on

the accompanying sheet of drawings, in which—

Figure 1 is a plan view of the paper blank constructed in accordance with my invention, showing the box in its knocked down form;

Figure 2 is a perspective view of the box portion in its set up relation as seen from the outside;

Figure 3 is a cross sectional view of the box in plan view and represents a showing taken on line 3*-3* of Figure 2;

Figure 4 is a cross sectional view of one corner of the box in its set up relation, disclosing the locking flap and the end panel construction, and represents a showing taken on line 4*-4* of Figure 3, and

Figure 5 is another view of a corner of the box but taken from a position which is at a 90° angle to that shown in Figure 4 and being taken on line 5*-5* of Figure 3.

The various novel features of the invention will be apparent from the following description and drawing and will be particularly pointed out in the appended claims.

Referring to the drawings, it will be noted that the blank from which my box is folded comprises a single piece of paper or cardboard 10 having a central portion 11 forming a main panel which will ultimately form the top or bottom portion of the box, the main panel 11 being provided with end panels 12 and side panels 13, these four panels being integral with the main panel but separated by hinge portions or folds in the blank shown at 14. Provided at the ends of the side panels 13 are flaps 15 integral with the side panels but being hinged as at 16 so that they may be bent at right angles thereto. On the upper edge of the end panels 12, an end flap portion 17 is provided integral therewith but hinged as at 18 so that it may be folded inwardly upon the flap 12 in a manner to enclose the flaps 15 and to hold the flaps 15 and the side and end panels respectively in set up position. Provided on the hinge portions 14 which join the side panels 13 to the main panel 11, four slits 19 are provided which are prefer-

ably formed with the cross cuts 20 in a manner to form a tongue portion 21 in the side panels. Hinged to the outer end of the end flap portion 17 is a locking flap 22, hinged as at 23 to the end flap 17 and integral therewith and being provided with wedge shaped extensions 24 at each end, as shown in Figure 1. Attention is called to the fact that the slit 25 is provided so as to 10 separate the flaps 15 from the edges of the end panel 12 and the end flap 17.

It will be noted from Figures 1 and 2 that the cross cuts 20 referred to above extend slightly on the opposite sides of the hinge 14. This is found to produce a very 15 efficient form of locking slit and permits greater freedom of movement of the tongue portions 21, but it is to be readily understood that the extension of the cross cuts is 20 not absolutely essential, it merely being necessary in practicing the present invention to provide slits extending parallel to the main panel of a size and location to accommodate the extensions of the locking flap 22.

25 The box portion formed from the above described blank constructed in accordance with my invention is readily set up from the blank, the hinges or folded portions being made by scoring or providing flexible 30 bend so as to render the various panels relatively easy to fold into their respective positions, and the locking means being of such a structure that the parts automatically assume their locked positions when they are 35 folded along the various bends into set up relation. It will be observed that according to Figure 3, when the box is set up the flaps 15 are enclosed between the end panel 12 and the end flaps 17 and that the locking 40 flap 22 is positioned at right angles to the end flap 17 and engages the inner surface of the main panel 11 with its end wedge portions 24 positioned in the slits 19 in a manner to bulge the flap 21 and abut the side 45 panel edgewise as at 25.

When it is desired to assemble the box, it is merely necessary to bend the side panels 13 at right angles to the panel 11, fold the corner flaps 15 into a position to abut the 50 inner surface of the end panel 12 after the end panel has been bent up at right angles in the same manner as panel 13. When this is done, the end flap 17 is folded over inwardly and is forced to overlie the panel 12 55 and to enclose the flaps 15, and in this course of movement, in view of the fact that the flap 17 is equal in height to the panel 12, the locking flap 22 engages the inside of the main panel 11 before the end flap 17 is completely seated. The continued movement of 60 the end flap 17 causes a bending on the hinge 23 so that the locking flap 22 assumes a position at right angles to the end flap 17 and engages the inside of the main panel 11 in a

plane parallel thereto. During the course 65 of this movement, the wedge extensions 24 on the ends cause a slight bulging of the side panels 13 and effect a separation thereof in opposition to the tendency of the side panels to remain in vertical position by virtue of 70 the natural resiliency of the material, until the wedge portions reach the slots 19 at which time they automatically displace the flaps 21 and engage edgewise the side panel 13 at the portion 25. It can be readily 75 understood that the locking flap 22 forms a reinforce for the end flap 17 and causes the parts to maintain their position as the displacement of the flaps 17 requires a bending of the locking flap 22 in the plane parallel 80 to the main panel. This affords not only a very durable and satisfactory form of set up box but is one that will permit the blanks to be readily set up and to be automatically locked in set up relation when the 85 parts are merely folded into their final position.

I claim:

1. In a folded paper box, a blank of bendable material comprising a main panel having side and end panels integrally hinged thereto at its margins, said side panels having inturned flaps at their ends and said blank being provided with a locking slit at the joining fold between said side panel and said main panel, said end panel being composed of three sections, the outermost being provided with wedge shaped lateral extensions adapted to engage in said slit whereby the two inner sections of said end panel may 100 be bent one upon the other to enclose said inturned flaps and to present said outermost portion in parallelism with said main panel with said wedge extensions positioned in said slits to form a box. 105

2. In a folding box, a blank of bendable material comprising a main panel and side and end panels hinged thereto, said side panels having inturned flaps adapted to be held by said end panels and being further provided with locking slits adjacent their jointure with said main panel, said end panels having a locking flap provided with wedge shaped extensions and adapted to be bent over to enclose said inturned flaps and to cause said locking flaps to engage the inside of said main panel so that the continued movement of the end panel into proper position causes the locking flap to assume a position parallel to said main panel and said extensions to automatically enter said slits by a wedging action to lock the parts in set up relation. 115

3. In a folded paper box, a blank of bendable material comprising a main panel having side and end panels integrally hinged thereto at its margins, said side panels having extensions adapted to be inturned 120

against said end panels, said blank being provided with locking slits at the joining folds between said side panels and said main panel, said end panel being composed of 5 three sections, the outermost being provided with lateral extensions adapted to engage in said slits whereby the two inner sections of said end panel may be bent one upon the other to enclose said extensions carried by said side panels and to present said outermost portion in parallelism with said main panel with said lateral extensions positioned in said slits to form a box. 10

Signed at Morris, Illinois, this 15th day of November, 1926.

LAWRENCE E. ARNESON.
